UNITED STATES PATENT OFFICE.

ALBERT FENIMORE ROCKWELL, OF NEW BRITAIN, CONNECTICUT, ASSIGNOR
TO THE NEW DEPARTURE BELL COMPANY, OF BRISTOL, CONNECTICUT.

ADJUSTABLE SUPPORTING-CLAMP.

SPECIFICATION forming part of Letters Patent No. 665,372, dated January 1, 1901.

Application filed May 9, 1900. Serial No. 16,101. (No model.)

To all whom it may concern:

Be it known that I, ALBERT FENIMORE ROCKWELL, a citizen of the United States, residing at New Britain, in the county of Hartford and 5 State of Connecticut, have invented certain new and useful Improvements in Adjustable Supporting-Clamps, of which the following is a specification.

The present invention relates to signaling 10 or other devices which are provided with means projecting therefrom designed to be actuated by the operator to operate the signal or other device. It particularly relates to a bell designed to be supported upon a vehicle in convenient reach of the hand or foot 15 of the operator, whereby when desired the bell may be sounded to sound an alarm. Bells of this type as now commonly constructed are provided with a radially-projecting lever or push-button which is actuated by the hand, and it is very important that such lever or push-button be capable of being positioned to suit the fancy or convenience of different users.

25 The object of the present invention is to so construct a signaling apparatus that the position of the projecting actuating device may be readily adjusted by the person who is using the same.

30 To the above end the present invention consists of the devices and combinations of devices, which will be hereinafter described and claimed.

In the accompanying drawings I have 35 shown the present invention as embodied in a bell, as that is the most common form of signaling device now used by the riders of bicycles and the like; but it is to be clearly understood that the present invention is not 40 limited in its application to bells.

In the drawings, Figure 1 shows in side elevation a bell designed to be mounted upon the handle-bar of a bicycle and embodying the preferred form of the present invention, 45 also showing the handle-bar in section. Fig. 2 shows a vertical section taken upon the line 2-2 in Fig. 3, with the gong shown in dotted lines. Fig. 3 shows a top plan view of the base of the bell, showing the clamp in dotted

lines, also showing a portion of the handle-bar. Fig. 4 shows an inverted plan view of the parts shown in Fig. 3, the handle-bar being shown in dotted lines. Fig. 5 shows a side elevation of the parts shown in Fig. 2 looking toward the left, and Fig. 6 shows in 55 perspective the band forming a portion of the clamp.

Similar reference-letters will be employed throughout the specification and drawings to designate corresponding parts.

In the drawings, A designates the bell as a whole, which comprises a gong a, a base b, and a laterally or radially projecting actuating device c, which is adapted to be engaged by the operator and moved to operate the bell 65 A to sound the alarm or signal. This actuating device c may be of any form dependent upon the form of the gong-sounding mechanism, and in the form shown, which illustrates a well-known type of bell, such actuating device consists of a lever pivoted within the base b and projecting through a cut-away portion b' of the base, it being provided outside of said base with a thumb-piece b², and within the base it is operatively connected with 75 the gong-sounding mechanism. (Not shown.) The bell A is supported upon a suitable support, usually the handle-bar B of a bicycle, it being held fixedly thereon by means of a clamp C.

In the present invention the adjustment of the position of the thumb-piece b² is secured by adjusting the gong and its base with relation to the clamp C, and the arrangement is such that when the clamp is tightened to secure the fixed position of the bell on the support or handle-bar B the bell will be immovably clamped and held from turning with relation to its clamp C.

As shown in the drawings, the clamp C comprises a circular plate c', which will be hereinafter called the "clamp-plate," which is fitted in a recess c², formed by stamping up the bottom of the base b, as clearly shown in Fig. 2 of the drawings. The wall of the recess c² is of such a shape that it forms a shoulder c³, and above said shoulder a horizontal flange c⁴, and within the angle formed by the

shoulder and flange the clamp-plate c' of the clamp is arranged to fit, as clearly shown in Figs. 2 and 4 of the drawings. The clamp-plate c' is slightly less in diameter than that portion of the wall of the recess c^2 formed by the shoulder c^3 , (see Fig. 4,) and is arranged to have a slight movement therein in a plane parallel to the bottom of the base for a purpose to be described. The clamp-plate c' is held in the recess by means of a plate c^5 , which may be mounted upon a rivet fixed in the bottom of the base b or, as shown in the drawings, upon the reduced portion e of the post e' , the lower end of the post being upset or headed, as at e^2 , below the plate c^5 . The post e' is fixedly mounted concentrically in the bottom of the base b and projects upwardly therefrom a sufficient distance to form a support for the gong a . The clamp-plate c' is held between the plate c^5 and the shoulder c^3 , formed on the post e' , the aperture c^{15} formed in said plate being slightly larger in diameter than the reduced portion of the post, so that said plate may move in the recess, as hereinbefore described, or the base may move with relation to the clamp-plate.

Projecting downwardly from the bottom of the clamp-plate c' is a box-like frame c^6 , said frame being of such a length and depth as to cover and protect the connections of the clamp-band c^{10} , as will be noted in Figs. 1 and 2. The forward portion of the side walls c^8 of the frame c^6 are cut out, forming curved seats c^9 , which rest upon the handle-bar B , each seat forming rests or fulcrums to resist the pull of the clamp-band on the post e' , as will be described. The flexible metallic clamp-band c^{10} is arranged to be connected at one end to a downturned hook c^{11} , formed on the plate c^5 , and at its opposite end said band is offset and provided with an opening c^{12} , through which passes a headed clamping-screw c^{13} , which is received in a threaded bushing or sleeve c^{14} , fixedly secured to the clamp-plate c' and depending therefrom within the frame c^6 . (See Fig. 2.)

From the foregoing description it will be noted that the bell and its base may be turned with relation to its clamp C to position the actuating device or thumb-piece b^2 at the point desired. After the bell has been so positioned the setting up of the screw c^{13} in its bushing c^{14} tightens the clamp-band c^{10} around the handle-bar B . The tendency of the strain thus placed upon the band c^{10} is to draw forward on the hook c^{11} of the plate c^5 , which acts to move the said plate and the rivet or post, together with the gong and base, forward over the clamp-plate c' , such movement being permitted by the slot c^{15} , and to forcibly bring the left-hand portion of said plate, as shown in the drawings, in contact with the shoulder c^3 , thus tightly clamping the bell to the handle-bar and at the same time preventing the bell from turning on its clamp.

It will be noted that the clamping of the

bell on the handle-bar and the fixing of the bell in the adjusted position on the clamp are secured through a single device and at a single operation.

When it is desired to change the position of the actuating device of the bell, all that is necessary to do is to loosen the screw c^{13} and grasping the bell A turn it upon its clamp C to bring the thumb-piece b^2 at the desired point, when upon setting up the screw the bell will be fixed both as to movement on the handle-bar and on the clamp.

The fixing of the gong in its adjusted position is obtained by bringing the clamp-plate at one side in engagement with the shoulder c^3 by the sliding movement of the base on the clamp-plate, which shoulder acts a stop to limit the relative sliding movement of the base and clamp-plate, and while in the accompanying drawings I have shown the clamp-plate as circular in form and a shoulder or stop as formed by a circular depression formed in the base, which is the best and preferred form now known to me, I desire to state that the present invention is not limited to such a construction, but includes all forms of adjustable clamps which embody means for permitting an axial adjustment of the base on the clamp-plate and also a relative sliding movement of the base and clamp-plate and a shoulder or stop for limiting the lateral sliding movement, with means for forcing the clamp-plate and shoulder or stop together.

Having described the construction and mode of operation of my invention, I claim as new and desire to protect by Letters Patent of the United States—

1. The combination with a base, of a clamp-plate, means for connecting the base and clamp-plate so as to permit a relative axial and sliding movement of said base and plate, a shoulder or stop carried by the base in position to engage the clamp-plate, a clamping-band connected at one end to the base and a screw carried by the clamp-plate and engaging the opposite end of the clamping-band, substantially as described.

2. The combination with a bicycle-bell comprising a base having a recess in its under side, of a clamp comprising a clamping-plate slightly less in diameter than the recess in the base and movably fitted therein, a clamping-band connected at one end to a plate immovably connected with the base, and a clamp-screw engaging the opposite end of the band and fitted to a threaded bearing in the clamp-plate, substantially as described.

3. The combination with a bicycle-bell having a base provided with a circular recess in its under side, of a clamp comprising a circular plate of less diameter than the recess and fitted in said recess, means permitting the bell-base to be turned with relation to its clamp and also to have a slight sliding movement with relation to the clamping-plate, a clamping-band connected at one end to the

bell-base, a clamp-box supported by the clamp-
ing-plate and having curved seats to rest on
the handle-bar of a bicycle, and a clamping-
screw carried by the clamping-plate and en-
5 gaging the opposite end of the clamping-band
substantially as described.

In witness whereof I have signed my name

to this specification in the presence of two
subscribing witnesses.
